DESIGN FOR A SUPPLEMENTARY METER CASING

Milton A. Pixley and Edward H. McCloud,
Columbus, Ohio

Application May 27, 1935, Serial No. 57,048

Term of patent 7 years

To all whom it may concern:

Be it known that we, Milton A. Pixley and Edward M. McCloud, citizens of the United States, residing at Columbus, in the county of Franklin and State of Ohio, have invented a new, original, and ornamental Design for a Supplementary Meter Casing, of which the following is a specification, reference being had to the accompanying drawing, forming a part thereof.

In the accompanying drawing:

Figure 1 is a front elevation of the supplementary meter casing showing our new design;
Figure 2 is a side elevation thereof;

Figure 3 is a section on the line 3—3 of Figure 1.

The stippled portions shown in Figures 1 and 2 designate translucent areas of the casing, while the central, unstippled area shown in Figure 1 designates a transparent portion of the front wall of the casing.

We claim:

The ornamental design for a supplementary meter casing as shown and described.
